UNITED STATES PATENT OFFICE.

GUSTAV B. WEDOW, OF CHICAGO, ILLINOIS.

ART OF LITHOGRAPHING.

1,416,311.

Specification of Letters Patent. Patented May 16, 1922.

Application filed February 7, 1921. Serial No. 443,038.

To all whom it may concern:

Be it known that I, GUSTAV B. WEDOW, a citizen of the United States, residing at 1718 North Richmond Street, Chicago, in the county of Cook and State of Illinois, have invented a new and useful Improvement in the Art of Lithographing, of which the following is a specification.

This invention relates to improvements in the art of lithographing and more especially to the lithographing of marbled or mottled paper, parchment, cloth or other materials such as are used, for example, for lining of book covers and similar purposes.

Heretofore, in performing such marbleizing, or in lithographing of such marbleized or mottled effects it was necessary carefully to draw or otherwise prepare on the lithographic stone, zinc plate, or other material used, a small design of the marbleized or mottled effect desired. It was then necessary to duplicate or repeat such design by copying or by lithographic processes in order to prepare a stone or zinc plate of the desired size which would be entirely covered with the desired marbleized or mottled effect. It will be seen that this process required a considerable amount of time and labor. In the first place, the preparation of the small portion of the desired design in itself was very difficult requiring great care and skill; and then the duplicating and repeating of this small portion in order to obtain a plate of the desired area required great skill, time and labor. In performing this process it was also difficult to make the large area appear continuous and not divided by lines marking the limits of the small portions from which it was made. It is obvious, of course, that it was possible to prepare in the first instance a stone or plate of the desired area with the desired effect by drawing or etching the design over the entire surface; but it is also obvious that such a method would have required so much time, care and skill as to make its use almost prohibitive.

By my improved method I am able to prepare very quickly, and at a minimum cost, a plate of zinc or other material with a beautiful and desirable marbleized or mottled effect over its entire surface so that such plate may be used, by means of the ordinary and well-known lithographing processes, for printing on paper or other sheets the design on the plate.

I have shown in the drawings one apparatus for use in connection with the carrying out of my improved process; although it is obvious that, without detracting from the spirit of this invention, other apparatuses which will perform the desired functions may be used just as well.

As shown in the drawings, Fig. 1 is a vertical sectional view of the apparatus referred to above, Fig. 2 is a view taken as indicated by the line 2 of Fig. 1, Fig. 3 is a fragmentary view of the plate used in carrying out my invention, and Fig. 4 is a fragmentary view of a completed print.

In the practice of my invention, I take a plate of zinc or other material suitable for lithographing purposes such as indicated by 10 and wrap the same about a cylindrical roller 11. The plate 10 is held in place on the roller by the bands 12 as shown; or it may be held in place in any other desired manner. The edges of the plate 10 may also be tacked to the roller if desired. The ends of the roller 11 are reduced in diameter and extended as indicated by 14, each extension having mounted on its outer end a wheel 15. I also provide a flat shallow trough or tray rectangular in shape such as is indicated by 16. The tray 16 is suitably supported by legs 17 and framing 18 and has mounted on its two sides the bracket rails or guides 19 in which the wheels 15 are adapted to roll. As shown in Fig. 2, it will be noted that when the wheels 15 are in place in the grooves formed by the guides 19 that the roller 11 will extend about one-half way down into the trough 16. I fill the trough 16 about one-half full of water as indicated by 25. I then float on the water a very small amount of ink. Not enough ink is floated on the water to make a complete layer of ink. Only enough ink is placed on the water to cause the ink to spread over the surface in separated portions, to form a mottled effect. The exact amount of ink required may be found by experimentation and may be varied in order to vary the character of the design which it is wished to produce. It is this spreading of the ink over the surface to give a mottled or marbelized appearance which finally gives the mottled or marbled final print through successive steps of the lithographing process. After enough ink has thus been floated on the water to give the desired effect the roller 11 with the zinc plate 10 fastened on it is put in place as

shown in the drawings with the wheels 15 resting on the rails 19. It should be stated here that the water 25 which was placed in the trough 16 must be of just sufficient depth 5 so that when the ink is floated on its surface and the roller 11 is put in place, as stated, the plate 10 will just touch the ink floating on the surface of the water. It is obvious, of course, that the apparatus must be level 10 and remain quiet. When the parts are thus arranged, the roller 11, as stated, is put in place at one end of the trough with the zinc plate 10 just touching the ink floated on the surface of the water. The roller is then 15 rolled the length of the trough thus causing the plate 10 to roll over the surface of the water bringing the entire area of the plate 10 into contact with the ink floating on the surface of the water. It should be stated 20 here also that the wheels 15 must be of the same diameter as the roller 11 so that as this rolling process above described is carried out there will be no friction between the surface of the plate 10 and the surface 25 of the water. As shown in the drawings, the thickness of the plate 10 may be disregarded; but it is obvious that if a thicker plate is used, the diameter of the wheels 15 should be equal to the diameter of the roller 30 11 extended through two thicknesses of the plate mounted thereon. It will be noted from the construction shown that where the wheels 15 are the same diameter as the roller 11 that the height of the water in the trough 35 should be substantially the same as the level of the tracks upon which the wheels 15 roll; in order to make the plate 10 just contact with the ink floating on the water.

The steps in the process described above 40 by which the entire area of the plate is brought into contact with the ink floating on the water serves to transfer the ink to the plate thus producing on the plate a marbled or mottled effect similar to the appearance 45 presented by the ink floating on the water.

After the ink has been put onto the plate, the plate is prepared for printing by any of the regular well known lithographic processes. A portion of the plate 10 as it appears after the ink has been put on it is 50 shown in Fig. 3; and Fig. 4 shows a part of a print, indicated by 30, taken from such a plate by any common lithographic process.

I have described above one method of 55 carrying out my invention, the main features of which are the forming of a mottled ink effect by floating a small quantity of ink on water, and the transferring of this ink to a lithographic plate by bringing the surface

of the plate in contact with the ink on the water. Such a disclosure is sufficient for anyone having a knowledge of lithographing processes in general to fully understand and comprehend my invention and carry out the same. In performing the operations described, however, it is obvious that, without detracting from the spirit of my invention, any of the steps in known lithographic processes may be used in conjunction with the same. For example, the surface of the plate may be prepared in any suitable manner by any well known lithographic process before it is brought into contact with the ink in order to make the ink more readily adhere to its surface; and after the plate is removed it should be "gummed up" with a sponge and solution of gum-arabic and water or otherwise prepared in order to partially solidify the ink and wash off the surplus water. It is obvious, however, that 75 after the ink has been placed on the plate, that the plate may be prepared for printing by any other suitable lithographing process.

I have found that it is some times desirable in the practice of my invention to make 80 the ink a little bit thinner than that ordinarily used in the well known processes of lithographing. Such thinning of the ink will cause it to spread over the surface of the water more readily and give a better or 85 more desirable marbled or mottled effect. I have also found that some times it is desirable to place in the water gum-arabic if it is found that the ink has a tendency to separate too much so that the proper mottled or 90 marbled effect is not obtained.

While I have shown and described certain 95 embodiments of my invention, it is to be understood that it is capable of many modifications. Changes therefore in the construction and arrangement may be made without departing from the spirit and scope of the invention as disclosed in the appended claim, in which it is my invention to claim all novelty inherent in my invention as 100 broad as possible in view of the prior art.

What I claim as new and desire to secure by Letters Patent is:

In the art of lithographing, the process of 105 producing a mottled or marbled effect on a lithographic plate which includes the floating of a small quantity of printing material on the surface of a liquid and the bringing of the surface of the plate into contact with such printing material.

In witness whereof I have hereunto set my hand and seal this 1st day of February, 1921.

GUSTAV B. WEDOW. [L. S.]
